Specification of Letters Patent.

Patented Nov. 15, 1921.

Application filed May 15, 1920. Serial No. 381,722.

To all whom it may concern:

Be it known that I, ALPHONSE DERUNGS, a citizen of France, residing at 161 Rue de Courcelles, Paris, France, have invented Improvements in or Relating to Rope Conveyers, of which the following is a clear, full, and exact description.

Wire rope systems with fixed cables employed in towing haulage and transporter plants, comprise one or more cables, or equivalent devices, secured at the ends to anchorages and resting on intermediate supports.

Whatever the stresses to which these systems are subjected, it is desirable that, on the one hand, the anchorages alone will take up the stresses acting in the longitudinal direction of the cables, and that, on the other hand, the intermediate supports will, as far as possible, only have to stand the vertical compression stresses, and not oblique stresses tending to subject them to flexion or tension.

It is the practice to put the cables under high permanent tension, in order to reduce to a minimum the oscillatory movement of the intermediate supports. Consequently, the initial sag of the cables is small.

Disadvantages arise from this method of procedure, which are the more serious in proportion as the transverse stresses on the cables are increased and as the intermediate supports are shorter.

In fact, every transverse stress sets up in the cables a longitudinal stress which is greater in proportion as the sag is smaller.

On the other hand, the shorter the supports the less their flexibility, and the less are they able to lend themselves to elastic deformations capable of compensating, partially at least, the fluctuations of tension in the cables of two adjacent spans.

The improved device forming the subject of the present invention insures, in the wire-rope system to which it is applied, a better distribution of the stresses, by enabling the cables to undergo certain longitudinal displacements in relation to their intermediate supports, with the result that the stresses acting on these supports are considerably lessened and consequently supports of less strength and economical construction may be employed.

Where the cables are subjected to transverse stresses, the new device enables a tem-

porary elongation of the cable to be obtained in any given span by the "give" of the cable in the adjacent spans, during, for example, the passage of a carriage, that is to say by the drawing in of those portions of the cable that are in the adjacent spans toward the span under consideration, in consequence of which the sag of the cable in the span under consideration is increased for the time being, and consequently the longitudinal tension, corresponding to the said transverse stresses on the cable, is reduced as far as possible.

According to this invention there is interposed between the cables and each of the intermediate supports, or a certain number of the latter, a mobile suspension device, pivoted on the support and enabling the cables to shift longitudinally or in the one or other direction, in relation to the support the said suspension device comprising either a plain or angle lever, an articulated system composed of several levers, or a combination of rigid and flexible members.

The accompanying drawings, which are given merely by way of example, represent diagrammatically several methods of carrying out the invention.

Figures 1, 2, 3 and 4 relate to a ropeway system comprising only a single rope. Fig. 1 is an elevation of one section of the line, Figs. 2, 3 and 4 being corresponding side elevations.

Figs. 5, 6, 7 and 7^a relate to a ropeway system comprising two united ropes, Fig. 5 being an elevation, Fig. 6 a side view and Fig. 7 a plan.

Referring to Figs. 1, 2, 3, it will be seen that the new ropeway system comprises intermediate supports *a*, arranged at intervals, at the top of which are mounted triangular suspension levers *c* pivoted at *b*. The single cable *d* is made up of a series of lengths secured to these levers at *e* and *f*, by means, for example, of ball joints. At the end of the line, the cable *d* is secured to fixed supports, which are not shown. If the line is very long, a certain number of the levers *c* may be rigidly attached to their respective supports, which are strengthened for this purpose, in order to form intermediate supports for the line.

A bracing wire *g* may be used to connect the pivotal points *b* together, in order to increase the rigidity of the system, if necessary.

The cable d is traversed by a carriage or tractor h , provided with any means whatsoever for insuring its remaining on the cable, and for operation thereof.

5 When the system is in repose, that is to say, when the carriage h is not in the section of the line under consideration, the members occupy the position represented by the full lines. The triangular levers c being acted 10 upon by equal forces—assuming the spans to be equal—take up the symmetrical, vertical position of equilibrium shown.

These forces, which are due solely to the weight of the cable, the levers and the permanent 15 tension of the cable are resolved, at each intermediate support, into a vertical resultant passing through the pivotal point of suspension b . If the tensions acting on the cable on either side of an intermediate 20 support cease to be equal, the resultant of the stresses is inclined relatively to the vertical, but always passes through the pivotal point b , the triangular lever also inclining toward the side of the predominating tension.

25 If the carriage h is in the section under consideration, the members of the system take up the position indicated by the dotted lines. In consequence of the supplementary tensions introduced into this span and the 30 adjacent spans by the carriage, the corresponding triangular levers tilt toward the carriage, and the points e , f , turning about the pivotal point b take up respectively the positions e^1 , f^1 .

35 As the result of this movement, the increased tension set up in the cable d by the presence of the carriage in the section under consideration, is partially transmitted to the adjacent spans, in such a way that the cable 40 is subjected to a more powerful tension, not only in that span, but also in a certain number of the adjacent spans on either side of this latter, the number of these spans varying with the conditions of the installation. 45 In each of the spans thus affected, the sag of the cable d is lessened while it is increased in the span occupied by the carriage, the result being a considerable reduction of the supplementary tension applied to the rope 50 in consequence of the presence of the carriage.

The new device produces therefore the following twofold effect:—

a. It lessens the reactions on the supports, 55 by transmitting the supplementary tensions put upon the cable to the spans adjacent to the one occupied by the carriage, and, if occasion arises, to the nearest anchorage.

b. It reduces the value of these supplementary tensions by increasing the sag in the span occupied by the carriage.

60 When the carriage h draws near a support, the triangular lever tilts in the opposite direction to its first movement and assumes, 65 very progressively, the position e^2 , f^2 , which

facilitates the passage of the carriage on to the arms e , f , which take the form of suspended rails as shown in Fig. 2.

It will be evident that the facility with which the carriage passes from one span to the next will depend on the length of the arms e , f , that is to say on the size of the angle e , b , f . The wider this angle, the easier the passage, but at the same time the possible amplitude of oscillation of the levers 75 c is correspondingly reduced. In fact, this oscillation is limited to the position in which the arms e , b and f , b are tangential to the cable; and for this limit, and in the vicinity of this limit, the cable tension is transmitted 80 almost completely to the support, which then necessitates the provision of bracing wires such as g .

The increased sag produced by the presence of the carriage in one of the spans is 85 greater in proportion as the amplitude of oscillation of the levers c is augmented, that is to say as the angle e , b , f is smaller.

Consequently, for each installation, it is necessary to select for the angle e , b , f a 90 value lying between the two limits resulting from the foregoing consideration, so that the carriage may pass easily from one span to the other and a sufficient increase in the sag can be obtained.

95 Fig. 2 shows the passage of the carriage on the rail e , f , on the right of a support.

Fig. 3 shows the carriage running on the cable between two supports.

In Fig. 4 the carriage is subjected to a 100 transverse pull exerted by a tow cable i , as in certain towings or haulage. In this case the levers c should be attached to their supports by pivots b , allowing of oscillation about two perpendicular axes, as in Cardan 105 joints, or any other equivalent device.

In Fig. 4 the carriage being towed and being subjected to the transverse pull of the tow cable, tilts sidewise, as do also the levers c . The cable leaves the vertical plane of repose, and its sag is determined not only by the weight of the carriage, but also by the oblique pull of the tow cable. It will be evident that, in this case, the sag in question may attain considerable dimensions.

115 In the modification illustrated by Figs. 5, 6, 7, the carriage or tractor h' is not carried by the cable, but runs either directly on the ground or on a suitable track, and propels itself by hauling on a taut fixed cable g , 120 while a second cable d supports an auxiliary carriage or traveler j .

In the modification shown in Fig. 7^a the tractor tows, for example, a boat k by means of a cable i connected to the traveler j . This latter transmits to the cable d the greater portion of the transverse pull due to the obliquity of the tow cable. The portion of the cable between the traveler j and the tractor or carriage h' may be of sufficient 130

length to make a very small angle with the direction of the cable *g*, that is to say to make the transverse pull on the tractor very small.

- 5 This method of carrying out the invention necessitates the use of a double system of cables and oscillating levers, similar to that described above, but superimposed and united.
- 10 A first system is constituted by a cable *g* and by levers *c* adapted to oscillate about the ball joints *l* which connect them with the standards *a*. The cable *g* is secured to the end of each lever by a pivot *b*, the other end 15 of the lever acting as the axis of a loose pulley *m*.

The second system is constituted by the cable *d* and triangular lever *n* adapted to oscillate on pivots *b*. Each of these triangular levers carries a track rail *o* resting on the corresponding pulley *m*.

The cable *d* consists of a series of lengths secured to the points *e* *f* of the levers *n*, with or without pivots.

- 25 The cable *g* is stretched taut, and the sags are very slight, that is to say the movements of oscillation of the pivoted points *b* are of only slight amplitude. The cable in this case supports practically no transverse 30 stresses beyond its own weight, but on the other hand, it has to withstand its permanent tension, increased by the longitudinal propulsion stress of the tractor.

The cable *d* is subjected to a permanent 35 tension appreciably smaller than that of the cable *g*. Under the action of the transverse stresses transmitted to it by the traveler *j*, it may sag temporarily to a considerable degree, that is to say, the movements of oscillation of the triangular levers *n* will be of 40 large amplitude.

As in the case of the construction shown in Figs. 1, 2, 3, the levers *n* comprise a rail *e*, *f* on which the traveler runs in passing 45 from one span to the next.

It will be evident that this arrangement of united cables presents the two-fold advantages of reducing the tensions on the cables to a minimum, and also reducing to a minimum the stresses applied to the intermediate supports, these latter having, in the case of the construction shown in Figs. 5, 6, 7, 7^a, merely to hold the cables at the desired height.

55 When the installation is at rest, the levers *c* and *n*, turning about the pivot *l*, continue to move until they come into contact with the edge of the supports *a*, so as to reduce the amount of space taken up by the installation.

60 Another manifest advantage of this arrangement is to permit the use of low supports, set very far apart, since the sag of the cable *d* is not large, except when it is subjected to the action of the traveler, and that

in this case the sag increases in the horizontal direction.

Moreover, it should be noted that the aggregation of cables and levers constitutes an elastic shock absorber, in which the effect of sudden fluctuations of stress is diminished and absorbed by the combined effect of the oscillation of the levers and the automatic equalization of the sag and tension of the cables under the effect of their own weight in the different spans.

Finally, it should also be noted that the two united systems described above, with reference to Figs. 5, 6, 7, 7^a may be employed separately.

Assuming that the contact of the tractor with the ground or the track gives it sufficient adhesion, it will be very evident that the cable *g* and the levers *c* can be dispensed with. The supports are then placed directly underneath the points of oscillation *l* and the system will then comprise only the cable *d* and the triangular levers *n*, which, when in repose, will rest against the supports *a* or be supported by a bracket, of any kind, fixed to the support and carrying a rail track for the pulley *m*.

This simplified device preserves the advantage of relieving the tractor from nearly the whole of the transverse pull due to the obliquity of the tow cable which tends to pull it toward the canal. It is specially applicable to the case of motor tractors running on the tow path or on a track parallel with the canal.

If, on the other hand, the tractor *h'*, running on a suitable track, is able to withstand the transverse pull due to the obliquity of the tow cable, but is unable to propel itself by simple adhesion to said track, the system comprising the cable *d* and the levers *n* may be suppressed together with the traveler *j*.

Only the system constituted by the cable *o* and the levers *c*, pivoted at *l* on the supports *a*, is retained with the exception that the pulleys *m* are no longer needed.

The second simplified device finds application for draft and in certain haulage plants.

It is to be understood that the fluctuations in the sag of the cable *d*, in the case of the construction illustrated in Figs. 5, 6, 7 are produced in the same manner as in the case of the construction illustrated in Figs. 1, 2, 3, 4, and that the system constituted by the cable *g* and the levers *c* is only a variation of the general case in which is found integrally the fundamental principle of the invention, consisting in interposing between the cable and its supports, a suspension device comprising a lever, or system of levers, articulated and adapted to turn in any direction, so as to lessen the strain both on the cable and on its supports.

The methods of carrying out the invention, represented in the accompanying drawings, are merely given by way of example, and the applications of the device may be modified.

Claims—

1. In a wire rope system, supports, levers pivoted on these supports, lengths of cable connecting these levers, a carriage running on the length of cable.
2. In a wire rope system, supports, triangular levers pivoted on these supports, length of cable connecting these levers, a carriage running on the length of cable.
3. In a wire rope system, supports, levers pivoted on these supports, lengths of cable connecting these levers, ball joints constituting the attachment of the said cable lengths and levers, a carriage running on the lengths of cable.
4. In a wire rope system, supports, levers pivoted on these supports, lengths of cable connecting these levers, a carriage running on the lengths of cable, a second cable connecting the articulations.
5. In a wire rope system, supports, articulations on these supports, levers rocking on these articulations, lengths of cable connecting these levers, a carriage running on these lengths of cable, a second cable, levers carrying this second cable.
6. In a wire rope system, supports, articulations on these supports, levers rocking on these articulations, lengths of cable connecting these levers, a carriage running on these lengths of cable, a second cable, levers carrying this second cable, and rocking on ball joints carried by the supports.
7. In a wire rope system, supports, articulations on these supports, levers rocking on these articulations, lengths of cable connecting these levers, a carriage running on these

lengths of cable, a second cable, levers carrying this second cable, and articulations common to both cables.

8. In a wire cable system, supports, articulations on these supports, triangular levers rocking on these articulations, lengths of cable connecting these levers, a carriage running on these cables, a second cable, levers carrying this second cable.

9. In a wire rope system, supports, articulations on these supports, levers rocking on these articulations, lengths of cable connecting these levers, a carriage running on these lengths of cable, a second cable, levers carrying this second cable, running rollers carried by one of the series of levers, and track rails carried by the other levers.

10. In a wire rope system, two conjugate cables, one of these cables taking up the longitudinal stresses and the other the transverse stresses, supports, and a combination of articulated levers connecting these cables to the said supports.

11. In a wire rope system, two conjugate cables, one of these cables taking up the longitudinal stresses and the other the transverse stresses, supports, a combination of articulated levers connecting these cables to the said supports, and a carriage running on one of these cables.

12. In a wire rope system, two conjugate cables, one of these cables taking up the longitudinal stresses and the other the transverse stresses, supports, a combination of articulated levers connecting these cables to the said supports, and a carriage running on one of these cables, a tractor bearing on the other cable.

The foregoing specification of my improvements in or relating to rope conveyers, signed by me, this 28th day of October 1919.

ALPHONSE DERUNGS.
